UNITED STATES PATENT OFFICE.

CHRISTIAN SEYERLE, OF GOWANDA, NEW YORK.

AUTOMATIC SAFETY-GUARD FOR EMBOSSED-PRESSES.

1,357,427.

Specification of Letters Patent. Patented Nov. 2, 1920.

Application filed March 3, 1919. Serial No. 280,341.

To all whom it may concern:

Be it known that I, CHRISTIAN SEYERLE, a citizen of the United States, residing at Gowanda, in the county of Cattaraugus, 5 State of New York, have invented certain new and useful Improvements in Automatic Safety-Guards for Embossing-Presses; and I do hereby declare the following to be a full, clear, and exact description of the invention, such as will enable others skilled 10 in the art to which it appertains to make and use the same.

This invention has reference to the art of printing and more particularly to an improved automatic safety guard for embossing presses or the like, to obviate the possibility of injury to the operator or plate printer by having the hands caught between the plates or platens of the machine, during 20 the stamping or embossing operation.

A further object of the invention is comprehended in the provision of a guard device for presses of the class described and more particularly an embossing and stamping 25 press constituting an apparatus for stamping and embossing paper, card board, book covers, letters and the like, of the type having a stationary upper platen and a movable lower platen adapted to be raised forcibly 30 in contact with the upper platen during the embossing operation, while the automatic safety guard embodies a novel arrangement of pendant guard elements carried by arms supported by the press frame and attached 35 to the lower or movable platen, so as to move downwardly, the guard elements, over the area between the platens and beneath the upper platen, so as to warn the operator by contact with his hands whereby to prevent 40 the hands from being caught between the platens, before the latter come together far enough to harm them, and which when the machine is open for inserting the material, the guard is entirely out of the way.

With the above objects and others in view, 45 as will appear, as the specification proceeds, the invention comprises novel combinations and arrangements of parts as will be herein-after more particularly set forth in detail 50 and claimed.

Reference is had to the drawings forming a part of the application, wherein like reference characters designate corresponding parts throughout the several views and 55 wherein:—

Figure 1 is a front elevation of an em-

bossing press, equipped with my improved automatic safety guard.

Fig. 2 is a side view thereof, with the plates or platens spaced apart in inoperative position, with the guard out of the way. 60

Fig. 3 is a fragmentary side elevation showing the parts in operative position.

Fig. 4 is a horizontal sectional view above the guard device. 65

Fig. 5 is a detail vertical sectional view taken on the line 5—5 of Fig. 1 and showing the mounting of the guard members proper, and

Fig. 6 is a detail view showing the manner 70 of attaching the device to the supporting frame of the embossing press.

By way of illustrating the application and use of the invention, in order that a full and clear understanding thereof may be had, 75 I have shown in the drawings, an embossing press generally designated by the letter P. This press is the usual type of apparatus for stamping and embossing paper, card board, book covers, letters and the like, or 80 may be of any particular type to which the invention is applicable with general use of the principles involved as will be hereinafter more particularly pointed out, so far as the same, is within the scope of the device as 85 claimed. I also desire to have it understood that the reverse arrangement of that to be hereinafter set forth, may be employed with equal facility and I desire to reserve the right to such modifications as will be 90 understood by those acquainted with the art.

In the form illustrated, as an embodiment of the principles of the invention, the embossing press is shown provided with a base 10 upon which are arranged side or 95 end plates 11 adapted to form a support for the lower movable platen 12, the bed plate 13 of which is designed to engage the upper edges of the supports, when the former is in its inoperative or lowermost position. 100 Arranged at the corners of the base 10, are a series of spaced parallel corner posts or uprights 14 which carry upon the upper ends thereof, the upper stationary bed plate 15 having the platen 16 on the bottom face 105 thereof and being hung or suspended from a top plate 17 engaged upon the corner posts or uprights 14 as shown. The lower or movable bed plate and platen are designed to be reciprocated vertically within the frame of 110 the machine, for the purpose of bringing the platens together, during the embossing op-

eration, for stamping or embossing, as is common in the art of plate printing.

In the construction of the automatic safety guard, there is applied to opposed 5 pairs of side posts or uprights, horizontal supporting strips 18 forming end members for the frame, and positioned parallel to the bed plates and platens and slightly above the lower face of the upper or stationary 10 platen. In order to mount the strips in position, there are provided at the ends thereof, clamps 19 comprising hinged jaws designed to coöperate with the outwardly bowed end portions of the strips, to envelop 15 the posts or uprights 14 and to fold against the inner faces of the strips adjacent to the extremities thereof, for securely holding the strips in fixed relation to the posts and thus the frame of the machine, through the medium 20 of clamping means or bolts 20 passed through co-acting or registering apertures in the adjacent portions of the strips and the hinged jaws of the clamps. In this manner, the strips are brought into binding 25 relation to the post, and they can be readily applied or removed, as will be found desirable or necessary, besides permitting the application of the device to embossing presses of general construction. It should also be 30 noted that the extremities of the strips are turned and bifurcated to accommodate an intermediate portion formed by reducing the end of the adjacent clamping jaw which is hinged thereto through the medium of the 35 hinge pin or the pindle 21, thus providing a binding connection, which is strong and durable.

Pivottally mounted upon the outwardly projecting bolts 20 and retained thereon by 40 nuts 22, at each side of the machine, there is a pair of levers 23, the pivots thereof being the clamping bolts 20 positioned adjacent to the posts, so that the levers are pivoted intermediately of their ends in spaced 45 parallel relation to the strips 18, and with their outer ends projecting forwardly and rearwardly of the machine for a purpose which will presently appear.

The inner ends are disposed in crossed 50 overlapping relation, and have formed therein, longitudinal slots 24. Fixed to each end of the lower or movable bed plate, is a bracket 25, each having a horizontal lower portion 26 receiving the fastening means 27, by which the brackets are rigidly attached 55 in an upwardly projecting or vertical position, to extend above the lower platen. The upper ends of the brackets are offset outwardly, being bent or extended outwardly 60 at right angles from the operative face of the lower platen and then upwardly at right angles to said outwardly extending portions, in spaced parallel relation outwardly of the strips or supporting members carried by the

frame, through the medium of the corner 65 posts as previously described.

The upwardly extended free extremities of the brackets are provided with rigid outwardly projecting pivot studs 28 engaging the slots 24, which latter allow for movements of the levers on fixed pivots rigidly spaced apart in fixed relation, as the movable platen is reciprocated. Suitable retaining means indicated at 29, are mounted upon the studs, in order to retain the levers from 75 displacement.

Upon the outer or free extremities of the levers, are arranged, the guards, which comprise upper bars or rods 30 fixed to the free extremities of the levers and preferably provided with threaded extremities engaged in coöperating apertures in opposed pairs of levers at the front and back of the machine, with clamping nuts 31 engaged on said extremities at either side of the 85 levers, thereby holding the parts in fixed relation with respect to the machine and with the levers in maintained parallel relation. Hung or suspended from the upper bars or rods 30 are lower bars or rods 32 90 which are disposed substantially in parallel relation to the upper rods and which are allowed compensatory movement relative to the upper guard rods, to prevent injury to the operator in serving the function of the 95 device, as will be more fully brought out. For this purpose, the lower guard rods are suspended at their ends by means of hangers 33, the same having slotted upper ends receiving or engaging movably the upper 10 guard rod inwardly of the clamping means at the extremities thereof, through the medium of slots 34, while the lower ends of the hangers are apertured to receive the extremities of the lower guard rods which are 10 held in fixed relation thereto, as by upsetting or riveting the ends of the lower guard rods in the manner shown in the drawings.

In the use and operation of the device, the lower bed plate and platen are resting 11 upon the supports 11, being moved downwardly by their weight or gravity, in conjunction with any suitable means for reciprocating the same as is common in the class 11 of embossing presses of this or any other desired type, to which the invention may be applied. In this connection, attention is called to the fact that the machine embodies upper and lower bed plates and platens, one of which is movable toward and 12 away from the other but it is to be understood that while I have illustrated the lower platen and bed plate as movable, this construction may be reversed or both may be made movable and the guard device applied 12 thereto with equal facility. However, in the construction shown, when the lower movable bed plate and platen are in the lowermost

position, inoperative and separated from the upper bed plate and platen, the brackets will move downwardly therewith, and by reason of the engagement of the studs of the brackets 5 in the slotted inner extremities of the levers, the latter will be drawn downwardly. This will be permitted by the arrangement of the slots in the levers as previously described, and the outer or free extremities of the 10 levers will be swung upwardly, thereby holding the guards proper in raised position above the operative faces of the platens. However, when the machine is operated and the platens are brought together, the lower 15 bed plate and platen will be moved upwardly, thus raising the brackets carried thereby and the studs, to swing the inner ends of the levers upwardly, thereby moving the outer extremities of the levers downwardly and together therewith, the guard 20 members arranged across the front and back portions of the machine. Normally, the lower guard rods are positioned above the operative face of the upper platen, which 25 is stationary, thereby being entirely out of the way to permit the insertion of the material to be acted upon. However, when the embossing operation is taking place, the guard will be arranged to overlie the co- 30 acting faces and as said movable plate is moving toward the stationary bed plate, the guard members will move downwardly, so as to contact with the operator's hands should they be in the way, thereby serving as a 35 warning, before the plates come together far enough to harm them. There would be sufficient weight to the guard proper, to move the hands out of the way if necessary, though usually they would be drawn 40 out of the way quickly and without probability of injury by coming between the co-acting platens. Injury, however, to the operator's hands would be prevented by the 45 guards proper, by reason of the slots arranged in the hangers, which permit the lower guard rods to move upwardly for this purpose. In this way, positive downward pressure by the guard member, upon the 50 hands, would be prevented. It is also to be understood that while I have illustrated the 55 guard members arranged at opposite sides of the front and back portions of the machine, one may be omitted or any number employed with equal facility and within the scope of the principles of invention involved. Furthermore, the device may be applied to one or both sides and if applied to both sides, can be taken apart quickly and with facility to operate on one side only if 60 occasion should arise.

What is claimed is:—

1. In an automatic safety device for presses having a member movable into co-operative relation to another, guards disposed beyond the ends of said members,

levers mounted between their ends on fixed pivots and connected at their outer ends with said guards, and pivotal connections between their inner ends and the movable member whereby the guards are moved to 70 intercept the spaces between said members before the latter are brought together.

2. In an automatic safety guard for embossing presses or the like having members, at least one of which is movable, supports 75 adapted to be mounted on opposite sides of the frame of said press, levers intermediately pivoted on the supports and having their outer ends projecting beyond said members and their inner ends pivotally connected with the movable member, and guards carried by said outer ends and extending along both ends of said members.

3. In an automatic safety guard for embossing presses or the like, having coöperating members, at least one of which is movable, supporting means engageable with the frame of the press at either side, levers pivotally supported thereby intermediately of their ends and having their outwardly 90 projecting ends extending beyond said members, a guard member carried by said ends and means of connection between the inner ends of the levers and the movable member.

4. In an automatic safety guard for embossing presses or the like, having coöperating members, at least one of which is movable, supporting means engageable with the frame of the press at either side, levers pivotally supported thereby intermediately 95 of their ends and having their outwardly projecting ends extending beyond said members, a guard member carried by said ends, said guard member being movably suspended for upward movement independently of the levers and disposed normally out of the area between the co-acting faces 100 of the members and adapted to move over and intercept the space between the co-acting members when the latter are operated.

5. An automatic safety guard for embossing presses or the like, having a frame structure, a movable platen and a stationary platen coöperating therewith; of strips having clamping means engageable with the frame structure at either side, a series of levers pivoted upon said strips and having compensating connection with the movable platen, and a guard member carried by the 115 levers and normally held out of the path of the space between the co-acting faces of the platens and adapted to intercept the spaces between the same before said faces are brought together and to overlie such 120 space when the platens are in operative position.

6. An automatic safety guard for embossing presses or the like, having a frame structure, a movable platen and a stationary 130

- platen coöperating therewith, strips having clamping means engageable with the frame structure at either side, brackets carried by the movable platen and having outwardly offset portions and similarly projecting studs, opposed pairs of levers pivoted to said strips at spaced points and having slotted inner ends engageable with the studs, rods connecting the free extremities of the levers which have their faces opposing each other, hangers having slots engageable with said rods, and guard rods connecting the lower ends of the hangers, as and for the purposes set forth.
7. The combination with an embossing press having top and bottom plates and corner posts connecting the same; a stationary upper bed plate and platen carried by the top plate, a lower movable bed plate and platen, means to support the latter in lowermost position, said movable platen being designed to be reciprocated vertically; of strips having hinged end portions engageable with the posts, connecting means

between said end portions and strips proper 25 forming clamping means to secure the strips above the operative face of the stationary platen horizontally positioned, levers pivoted to said clamping means outwardly of the strips and posts, connecting means between 30 the movable platen through the medium of its bed plate to cause movement of the latter when the bed plate is reciprocated to bring the platen thereof into contact with the stationary platen for operation upon the work, 35 connecting means for the levers holding the same in spaced relation rigidly, and pendant pivotal guard members carried by said connecting means for movement in an opposite direction from the movable bed plate and 40 platen.

In testimony whereof, I affix my signature, in the presence of two witnesses.

CHRISTIAN SEYERLE.
